[57] ABSTRACT

A colloid mill is characterized by a stator and a rotor disposed along an axis. The stator has a re-entrant conical surface with grooves extending from the outer periphery to an inner axial opening. The rotor is keyed to a shaft that extends through the axial opening of the stator and has vanes with outer edges that are closely adjacent to and in registration with the conical surface of the stator. The arrangement is such that the high speed rotation of the rotor causes fragmentation of colloid particles in a fluid that is driven under pressure from an inlet through the small clearance between the conical surface of the stator and the vanes of the rotor and through the clearance between the axial opening of the stator and the shaft of the rotor.

ULTRA FINE COLLOID MILL

BACKGROUND AND SUMMARY

The present invention relates to colloid mills and, more particularly, to colloid mills capable of producing ultra fine colloids.

Conventional colloid mills have been used to produce emulsions characterized by particle sizes ranging from submicron to one or two microns. Typically, liquid is refined by passage through an adjustable gap between a solid rotor and a solid stator. If the gap is too narrow, the material will not feed. If the gap is too wide the degree of refinement is not adequate.

The primary object of the present invention is to provide a colloid mill, in which the liquid being refined is characterized by an interface between the rotor and the stator. On one side of the interface, the liquid is retained by the adjacent face of the stator in stationary position. On the other side of the interface, the liquid is retained by the adjacent face of the rotor for movement with respect to the stator. The result, in effect, involves liquid stator and rotor faces, which enable continuous feeding but between which is no gap. Specifically, the stator has a re-entrant conical surface with grooves extending from the outer periphery to an inner axial opening. The rotor is keyed to a shaft that extends through the axial opening of the stator and has vanes with outer edges that are closely adjacent to and in registration with the conical surface of the stator. The grooves tend to retain liquid in contiguity with the stator relatively stationary. The vanes tend to carry liquid in contiguity with the rotor for movement with respect to the stator. The arrangement is such that colloid particles in a fluid, advancing from an inlet to an outlet, are unusually effectively fragmented down to sizes that characteristically may be as small as one-tenth of a micron.

Other objects of the present invention will in part be obvious and will in part appear hereinafter.

The invention accordingly comprises the apparatus, and process together with their components, steps and interrelationships, which are exemplified in the present disclosure, the scope of which will be indicated in the appended claims.

BRIEF DESCRIPTION OF THE DRAWINGS

For a fuller understanding of the nature and objects of the present invention, reference is made to the accompanying drawings wherein:

FIG. 1 is a perspective view, partly broken away, of the head of a colloid mill constructed in accordance with the present invention;

FIG. 2 is a cross sectional view of the apparatus of FIG. 1 taken substantially along the line 2-2 of FIG. 1;

FIG. 3 is an end view of the head of the apparatus shown in FIG. 2, the view being taken substantially along the line 3-3 of FIG. 2;

FIG. 4 is an end view of a rotor of the apparatus of FIG. 2, the view with components omitted being taken substantially along the line 4-4 of FIG. 2;

FIG. 5 is a cross sectional view of a stator of the apparatus of FIG. 1, the cross section being taken at the axis of the apparatus;

FIG. 6 is an end view of the stator of FIG. 5;

FIG. 7 is a side elevation of a complete apparatus in which a colloid mill, of the type shown in FIG. 1, is a part;

FIG. 8 is an end elevation of the apparatus of FIG. 7; FIG. 9 is a side elevation of an alternative complete apparatus in which a colloid mill, of the type shown in FIG. 1, is a part; and

FIG. 10 is an end view of the apparatus of FIG. 9.

DETAILED DESCRIPTION

As shown in FIG. 1, the illustrated colloid mill comprises a casing 20 that defines a path 22 through which a dispersion having a liquid outer phase is fed for the purpose of refinement between an inlet port 24 and an outlet port 26. Housing 20 includes five aligned, centrally opened disks, which are flush peripherally in order to define an outer cylindrical surface. These disks include an inlet ring 28, a first stator ring 30, a second stator ring 32, an outlet ring 38 and a sealing ring 40. Each preceding ring is seated on the succeeding ring by means of a peripheral shoulder recess 42 in the inner surface of the preceding ring and a peripheral shoulder ledge 44 in the outer surface of the succeeding ring. Also adjacent rings are hermetically sealed by groove and O-ring arrangements 46.

Stators 30 and 32 each provides a re-entrant conical face 48 having a central aperture 50. Conical face 48 is provided with: grooves 52, which extend from a position adjacent to the outer periphery of conical face 48 to a position adjacent to central aperture 50; and grooves 53, which are T-shaped and which extend from a T-head, that is positioned between the outer periphery of the conical surface and the inner aperture, to selected ones of a series of parallel grooves 36 in the face of aperture 50.

Rotatable within the regions defined by conical faces 48 of rings 30, 32 are rotors 55, 57 each of which provides a series of six vanes 56, FIG. 4, the outer edges 58 of which are in close adjacency with conical surface 48. Edges 58 are disposed along a theoretical conical surface that is closely spaced to the surface 48 of the stator.

Extending rearwardly from sealing ring 40 is a bearing housing 60. Each rotor 55, 57 is keyed to the free end of a shaft 62. Shaft 62 is driven at its other end 64, which extends through bearing housing 60, where it is journaled in two ball bearing units 66, 68. Shaft 62 extends through the central opening in sealing disk 40, through the collecting cavity of outlet disk 38, and through the refining regions encompassed by stators 32, 30, within which rotors 55, 57 are carried by shaft 62. The free end of shaft 62 extends into the cavity of ring 30 in cantilever fashion. As shown, stators 32 and 30, have a central bore through which shaft 62 projects. As shown, the shank 65 of rotor 57 abuts against the shank 67 of rotor 55 and the shank 67 of rotor 55 abuts against a shoulder 70 of shaft 62. The rotors are locked into their positions on shaft 62 by a retainer ring 74 which is clamped against shank 65 of rotor 57 by a nut 76, which is turned onto a threaded stub of shaft 62.

As shown in FIG. 2, bearing housing 60 is fastened, by webs 61 to sealing ring 40. Rings 40, 38, 32, 30, 28 are tied together by bolts 82 (one shown in FIG. 2) that extend through aligned bores in the rings, opposite threaded ends of the bolts being meshed with nuts 84, 86. As shown in FIG. 3, there are eight such nut and

bolt ties. As best shown in FIG. 2, O-ring at 90 and seals at 92, and 94 hermetically isolate the bearing housing from the atmosphere. Mechanical seal 34 and O-ring 88 seal the milling cavity 22 from the atmosphere. Seals 96, 98 create a chamber behind mechanical seal 34 for the introduction of a flush fluid to protect seal 34. A gravity feed lubricant supply 100 communicates with the shaft through a bore 102 in sealing ring 40.

As shown in FIG. 4, each of rotors 55, 57 has six vanes 56, each of which is disposed along a plane that is offset from and parallel to a line radially through the axis of rotation. The lines of orientation of blades 56 and the lines of orientation of grooves 52, 53 are arranged so that as the blades spin, the lines are parallel, thereby creating rapid pressure changes within the grooves. The centrifugal force created by the revolving turbine blades 56 imparts velocity to the fluid thereby pumping fluid from inlet 24, through cavity 22 and through outlet 26. As shown in FIG. 5 and 6, each stator is provided with a cylindrical outer periphery 104 having a plurality of grooves 106, each of which opens at the outer extremity of the cylindrical surface of revolution and defines a point at the inner extremity of the cylindrical surface of revolution.

OPERATION

In operation, the cylindrical surfaces of revolution of the stator and rotor are coated with fluid layers that contact each other but that move with respect to each other. The result is an extremely high shear gradient at the interface between the moving and stationary fluid layers. The arrangement is such that the direction of flow of the refined material is counter to the centrifugal force. As a result, back pressure and retention time are increased to produce more work in the fluid.

FIGS. 7 and 8 illustrate an arrangement of apparatus within which the colloid mill of FIG. 1 is incorporated. As shown in FIG. 7, this colloid mill is shown at 110 as having a transmission 112 which is driven through a pulley 114 by an endless belt 116 and a pulley 118 that is keyed to the shaft of a motor 120. In this arrangement as shown in FIG. 8, motor 120 is supported within a frame 122 on a cross plate 124 and colloid mill 110 is supported above it on a cross piece 126. An alternative embodiment is shown in FIGS. 9 and 10, wherein a colloid mill 128 is driven through a pulley 130, a belt 132 and a pulley 134 by a motor 136, which is mounted upon a base 138 that also supports colloid mill 128.

The present invention thus provides an improved colloid mill capable of producing ultra fine colloid particles. In operation the unit is belt driven to produce speeds of 3,550 to 4,550 revolutions per minute. At 4,550 revolutions per minute, the peripheral velocity of the blade tip is 160 feet per second. As a result fluid enters inlet 24 and flows then through the first sub-chamber in which rotor 57 operates, next through the second sub-chamber in which rotor 55 operates, then through the third sub-chamber which communicates with outlet 26, from which the ultra-refined liquid is released.

Since certain changes may be made in the foregoing disclosure, without departing from the scope of the invention herein, it is intended that all matter shown in the accompanying drawings and described in the foregoing specification be interpreted in an illustrative and not in a limiting sense.

What is claimed is:

1. A colloid Mill comprising a casing disposed along an axis, a shaft disposed for rotation along said axis within said casing, at least a stator disposed about said shaft, said stator defining a re-entrant conical surface of revolution, and a re-entrant cylindrical surface of revolution in communication with each other said surfaces having therein grooves, a first series of said grooves extending from the forward periphery of said re-entrant conical surface to a medial portion thereof, a second series of said grooves extending from a medial portion of said re-entrant conical surface to the rearward periphery thereof, said first series of said grooves and said second series of said grooves being isolated from each other, at least a rotor keyed to said shaft for rotation therewith, said rotor having spaced blades, the outer edges of said blades being disposed in a conical surface of revolution, said concial surface of any stator and said conical surface of any rotor being adjacent, rotation of said rotor causing refinement of colloid particles in a fluid passing from an inlet at one extremity of said shaft through at least a chamber defined by said stator and within which said rotor rotates, between said conical surfaces and through an outlet that is disposed in an axis perpendicular to the axis of said shaft.
2. The colloid mill of claim 1 wherein said conical surface of said stator and said conical surface of said rotor are spaced at most .01 inch from each other.
3. The colloid mill of claim 1 wherein, in sequence, there are a plurality of stators, a plurality of rotors and a plurality of chambers.
4. The colloid mill of claim 1 wherein one portion of said shaft is journaled for rotation and the portion of said shaft within said chamber extends to a free extremity thereof.
5. The colloid mill of claim 1 wherein said slots include a first series of slots extending from a point adjacent to the outer periphery of said conical surface of said stator to a point adjacent to the inner aperture of said conical surface of said stator.
6. A colloid mill comprising a casing disposed along an axis, a shaft disposed for rotation along said axis within said casing, at least a stator disposed about said shaft, said stator defining a re-entrant conical surface of revolution, said surface having therein grooves, at least a rotor keyed to said shaft for rotation therewith, said rotor having spaced blades, the outer edges of said blades being disposed in a conical surface of revolution, said conical surface of any stator and said conical surface of any rotor being adjacent, rotation of rotor causing refinement of colloid particles in a fluid passing from an inlet at one extremity of said shaft through at least a chamber defined by said stator and within which said rotor rotates, between said conical surfaces and through an outlet that is disposed in an axis perpendicular to the axis of said shaft, one of said series of said grooves extending from a T-head medially located between the outer periphery of said conical surface of said stator and the inner aperture of said conical surface of said stator to a point communicating with said inner aperture of said stator.

7. The colloid mill of claim 1 including an inlet ring defining said inlet, a stator ring defining said reentrant conical surface and an outlet ring defining said outlet, the outer peripheries of said inlet ring, said stator ring, and said outlet ring being of like circular cross section and being registered to define an outer cylinder.

8. A colloid mill comprising a casing disposed along an axis, said casing including a plurality of aligned rings, a shaft disposed for rotation along said axis within said casing, one of said rings defining a stator disposed about said shaft, said stator defining a re-entrant conical surface of revolution, and a re-entrant tubular surface of revolution in communication with each other, said surfaces having therein grooves, a first series of said grooves extending from the forward periphery of said re-entrant conical surface to a medial portion thereof, a second series of said grooves extending from a medial portion of said re-entrant conical surface to the rearward periphery thereof, said first series of said grooves and said second series of said grooves being isolated from each other, at least a rotor keyed to said shaft for rotation therewith, said rotor having spaced blades, the outer edges of said blades being disposed in a conical surface of revolution, said conical surface of any stator and said conical surface of any rotor being adjacent, another of said rings defining an inlet and another of said rings defining an outlet, rotation of rotor causing refinement of colloid particles in a fluid passing from said inlet at one extremity of said shaft through at least a chamber defined by said stator and within which said rotor rotates, between said conical surfaces and through said outlet.

9. The colloid mill of claim 8 wherein said conical surface of said stator and said conical surface of said rotor are spaced at most 0.01 inch from each other.

10. The colloid mill of claim 8 wherein, in sequence, there are a plurality of stators, a plurality of rotors and a plurality of chambers.

11. The colloid mill of claim 8 wherein one portion of said shaft is journaled for rotation and the portion of said shaft within said chamber extends to a free extremity thereof.

12. The colloid mill of claim 8 wherein said slots include a first series of slots extending from a point adjacent to the outer periphery of said conical surface of said stator to a point adjacent to the inner aperture of said conical surface of said stator.

13. A colloid mill comprising a casing disposed along an axis, said casing including a plurality of aligned rings a shaft disposed for rotation along said axis within said casing, one of said rings defining a stator disposed about said shaft, said stator defining a re-entrant conical surface of revolution, said surface having therein grooves, at least a rotor keyed to said shaft for rotation therewith, said rotor having spaced blades, the outer edges of said blades being disposed in a conical surface of revolution, said conical surface of any stator and said conical surface of any rotor being adjacent, another of said rings defining an inlet and another of said rings defining an outlet, rotation of rotor causing refinement of colloid particles in a fluid passing from said inlet at one extremity of said shaft through at least a chamber defined by said stator and within which said rotor rotates, between said conical surfaces and through said outlet, one of said series of said grooves extending from a T-head medially located between the outer periphery of said conical surface of said stator and the inner aperture of said conical surface of said stator to a point communicating with said inner aperture of said stator.

14. A colloid mill comprising a casing disposed along

an axis, said casing including a plurality of aligned rings, a shaft disposed for rotation along said axis within said casing, a plurality of said rings defining a plurality of stators disposed about said shaft, said stators defining reentrant conical surfaces of revolution, and re-entrant tubular surfaces of revolution said surfaces each having therein grooves, a first series of said grooves extending from the forward periphery of one of said re-entrant conical surfaces to a medial portion thereof, a second series of said grooves extending from a medial portion of said one of said re-entrant conical surfaces to the rearward periphery thereof, said first series of said grooves and said second series of said grooves being isolated from each other, a plurality of rotors keyed to said shaft for rotation therewith, each said rotor having spaced blades, the outer edges of said blades being disposed in a conical surface of revolution, said conical surface of any stator and said conical surface of any rotor being adjacent, another of said rings defining an inlet and another of said rings defining an outlet, rotation of rotor causing refinement of colloid particles in a fluid passing from said inlet at one extremity of said shaft through at least a chamber defined by said stator and within which said rotor rotates, between said conical surfaces and through said outlet said conical surface of said stator and said conical surface of said rotor are spaced at most .01 inch from each other, one portion of said shaft being journaled for rotation and the portions of said shaft keyed to said rotors extending to a free extremity thereof.

15. The colloid mill of claim 14 wherein said slots include a first series of slots extending from a point adjacent to the outer periphery of said conical surface of said stator to a point adjacent to the inner aperture of said conical surface of said stator.

16. A colloid mill comprising a casing disposed along an axis, said casing including a plurality of aligned rings, a shaft disposed for rotation along said axis within said casing, a plurality of said rings defining a plurality of stators disposed about said shaft, said stators defining re-entrant conical surfaces of revolution, said surfaces each having therein grooves, a plurality of rotors keyed to said shaft for rotation therewith each said rotor having spaced blades, the outer edges of said blades being disposed in a conical surface of revolution, said conical surface of any stator and said conical surface of any rotor being adjacent, another of said rings defining an inlet and another of said rings defining an outlet, rotation of rotor causing refinement of colloid particles in a fluid passing from said inlet at one extremity of said shaft through at least a chamber defined by said stator and within which said rotor rotates, between said conical surfaces and through said outlet said conical surface of said stator and said conical surface of said rotor are spaced at most .01 inch from each other, one portion of said shaft being journaled for rotation and the portions of said shaft keyed to said rotors extending to a free extremity thereof, one of said series of said grooves extending from a T-head medially located between the outer periphery of said conical surface of said stator and the inner aperture of said conical surface of said stator to a point communicating with said inner aperture of said stator.
